United States Patent Office

Des. 222,141
Patented Oct. 5, 1971

222,141

COMBINED TAPE PLAYER AND SPEAKER ENCLOSURE THEREFOR

Lawrence Mace, New York, N.Y., assignor to
Meredith Corporation

Filed Feb. 24, 1970, Ser. No. 21,632

Term of patent 14 years

Int. Cl. D14—02

U.S. Cl. D26—14

FIG. 1 is a front elevation of a combined tape player and speaker enclosure therefor showing my new design;

FIG. 2 is a rear elevation thereof;

FIG. 3 is a top plan view thereof;

FIG. 4 is a bottom plan view thereof;

FIG. 5 is a left side elevation thereof;

FIG. 6 is a front elevation with the case in an open position; and

FIG. 7 is a side elevation thereof.

I claim:

The ornamental design for a combined tape player and speaker enclosure therefor, as shown.
